Primary Examiner — Kevin K Rudzinski*Assistant Examiner* — Paul D Bohannon(74) *Attorney, Agent, or Firm* — Schwabe Williamson & Wyatt, PC(57) **CLAIM**

The ornamental design for a park bench, as shown and described.

DESCRIPTION

FIG. 1 is a perspective view of a first embodiment of the park bench;

FIG. 2 is a left side view of the park bench;

FIG. 3 is a front view of the park bench;

FIG. 4 is a rear view of the park bench;

FIG. 5 is a top plan view of the park bench;

FIG. 6 is a bottom view from the underside of the park bench;

FIG. 7 is a perspective view of a second embodiment of the park bench;

FIG. 8 is a left side view of the park bench;

FIG. 9 is a front view of the park bench;

FIG. 10 is a rear view of the park bench;

FIG. 11 is a top plan view of the park bench; and,

FIG. 12 is a bottom view from the underside of the park bench.

The broken line showing of support brackets and support bracket fasteners is for the purpose of illustrating environmental structures and forms no part of the claimed design.

1 Claim, 4 Drawing Sheets---
